UNITED STATES PATENT OFFICE.

OTIS A. MYGATT, OF NEW YORK, N. Y.

DESIGN FOR A SHADE, REFLECTOR, OR THE LIKE.

43,965.

Specification for Design.

Patented May 6, 1913.

Application filed July 1, 1909. Serial No. 505,509. Term of patent 14 years.

To all whom it may concern:

Be it known that I, OTIS A. MYGATT, residing at New York, in the county of New York and State of New York, have invented and produced a certain new and useful Design for a Shade, Reflector, or the Like, of which the following is a specification, reference being had therein to the accompanying drawings.

The drawing is an elevation of a shade reflector or the like embodying my design.

The design consists in making a one piece glass shade divided horizontally into two distinct sections, a corrugated straight sided or substantially cylindrical skirt portion, integral to and strongly contrasting with an

upper flared out portion having on its outer surface horizontal corrugations.

The object is to reproduce in an integral glass article the effect given by a flared out prism glass shade with separately attached hanging fringe composed of individual glass prisms.

I claim—

The ornamental design for a shade, reflector or the like, substantially as shown and described.

OTIS A. MYGATT.
